UNITED STATES PATENT OFFICE.

MISAEI AUTHIER, OF MONTREAL, CANADA.

DESIGN FOR A SLIPPER.

SPECIFICATION forming part of Design No. 25,236, dated March 3, 1896.

Application filed November 7, 1895. Serial No. 568,235. Term of patent 14 years.

To all whom it may concern:

Be it known that I, MISAEI AUTHIER, a subject of the Queen of Great Britain, residing at the city of Montreal, in the district of Montreal and Province of Quebec, Canada, have 5 invented and produced a new and original Design for Slippers, of which the following is a specification, reference being had to the accompanying drawings, forming part thereof.

The slipper comprises a front toe portion a with sole b and heel-counter portion c with the usual heel, and the leading feature thereof 15 consists of a raised ornamental embossment or pattern crimping the bow and floral sprays e across the front portion thereof.

What I claim is—

The design for a slipper substantially as 20 shown and described.

MISAEI AUTHIER.
